ATTORNEY

UNITED STATES PATENT OFFICE.

GEORGE LEMUEL McCUALEY, OF PLEASANT PLAINS, ARKANSAS.

WRENCH.

SPECIFICATION forming part of Letters Patent No. 449,257, dated March 31, 1891.

Application filed December 3, 1890. Serial No. 373,482. (No model.)

To all whom it may concern:

Be it known that I, GEORGE LEMUEL McCUALEY, a citizen of the United States, residing at Pleasant Plains, in the county of Independence and State of Arkansas, have invented certain new and useful Improvements in Wrenches; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention has relation to ratchet-wrenches; and it consists in the novel construction and arrangement of its parts.

In the accompanying drawings, Figure 1 is a face view of my invention. Fig. 2 is a detail sectional view of the head of the wrench, and Fig. 3 is an end view of the wrench, showing the three cog-wheels in their relative position. Fig. 4 is a detail view of the inside of the jaw C'.

25 My invention is described as follows: It consists of a body A, having in one end the perforation a and on the other the handle a', and about its middle it has the cylindrical enlargement, in which is a socket a². Said 30 socket contains a coil-spring a³, the lower end of which rests on the bottom of said socket and the upper end presses against the lower end of the rod a⁴, the upper end of which is pivoted to the double pawl a⁵, which in turn is pivoted to the body A at a⁶. Said pawl a⁵

35 is provided with the arms a⁷ and a⁸, adapted to play in the ratchets of the wheel B. Said wheel B is perforated in its middle and has on one face the sleeve or perforated extension b, which passes through the perforation a of the body A, and on its projecting end is 40 screwed the nut b'. On the other face of said wheel and attached thereto (see Fig. 1) are the guides b² b³, each provided with a lug b³.

45 Loosely working on said guides b² are the sliding jaws C C', the jaw C' having on its outer face the meshing cog-wheels c c' c, the cog-wheel c' is journaled to the side of said jaw, and the wheels c c are attached to the 50 ends of the threaded bolts c², which pass

through threadless perforations in the jaw C' and work in the threaded perforations of the jaw C. Said bolts c² are held in place by the shoulders c³, countersunk in the inner face of the jaw C', and said jaw also has the depressions c⁴ to receive the lugs b³ when the two jaws come together. The said wheel B, the slides b², and the sleeve b are made in one solid piece.

55 My invention is operated as follows: The double pawl a⁵ is adjusted to the direction in which the nut is to be turned and then the jaws are made to fit the nut. This is done by turning one of the cog-wheels c with either hand, and the wheel c' will transmit the same motion to the opposite cog-wheel c, and the jaws will be brought together simultaneously. If the threaded end of the bolt on which the nut is to be screwed should extend beyond the outer face of the nut, it passes 70 through the perforated wheel B and extension b.

The advantages of this wrench consist, first, in the two threaded bolts c² operated by one motion; second, in its strength, which is 75 attained by having the ratchet-wheel B, extension b, and the guides b² all made in one piece, and, lastly, that the shoulders c³ are countersunk in the jaw C', and the two jaws are provided with depressions to receive the lugs b³, so that said jaws may be brought absolutely together.

Having described my invention, what I claim as new, and desire to secure by Letters Patent, is—

85 1. A wrench consisting of the body A, having the perforation a, handle a', and enlargement provided with the socket a², double pawl a⁵, pivoted to the body A, and having the arms a⁷ and a⁸, rod a⁴, one end pivoted to the pawl a⁵, and the other end extending into socket a², spring a³, its lower end resting on the bottom of socket a² and its upper end engaging the lower end of rod a⁴, ratchet-wheel B, having the extension b, passing through the perforation a, and held therein by the nut b', and guides b², having the lugs b³, sliding jaws C' and C, having suitable perforations for the threaded bolts c², threaded bolts c², having on one end the cog-wheels c, and cog-wheels 95 100

c', adapted to mesh with both cog-wheels *c*, substantially as shown and described, and for the purposes set forth.

2. In combination with a wrench having the 5 sliding jaws *C* and *C'*, body *A*, and double pawl *a*⁵, the perforated ratchet-wheel *B*, having the perforated extension *b*, and guides *b*², all made in one solid piece, substantially as shown and described, and for the purposes 10 set forth.

3. In combination with a wrench, substantially as shown and described, the sliding jaws

C' and *C*, operated by the two threaded bolts *c*², each having on one end a cog-wheel *c*, and the cog-wheel *c'* meshing with the cog-wheel *c*, substantially as shown and described, and for the purposes set forth. 15

In testimony whereof I affix my signature in presence of two witnesses.

GEORGE LEMUEL McCUALEY.
